UNITED STATES PATENT OFFICE.

BARTON P. JENKS AND FREDERICK R. ROBERTS, JR., OF CONCORD, NEW HAMPSHIRE,
ASSIGNORS TO WILLIAM B. DURGIN COMPANY, OF CONCORD, NEW HAMPSHIRE, A
CORPORATION OF NEW HAMPSHIRE.

DESIGN FOR A SPOON, FORK, OR SIMILAR ARTICLE.

No. 39,673.

Specification for Design.

Patented Dec. 1, 1908.

Application filed August 21, 1908. Serial No. 449,749. Term of patent 14 years.

To all whom it may concern:

Be it known that we, BARTON P. JENKS and FREDERICK R. ROBERTS, Jr., both citizens of the United States, and both of Concord, in the county of Merrimack and State of New Hampshire, have invented a new, original, and ornamental Design for Spoons, Forks, and Similar Articles, of which the following is a specification, reference being had to the accompanying drawing, forming part thereof.

The figure is a plan view of a spoon, show-

ing our new design. Said figure also illustrates by dotted lines the design as adapted for a fork.

We claim:

The ornamental design for a spoon, fork, or similar article, as shown.
